(57) **CLAIM**

The ornamental design for a tissue suspension adaptor, as shown and described.

DESCRIPTION

FIG. 1 is a front perspective view of a tissue suspension adaptor in accordance with the present invention; FIG. 2 is a front view thereof, the rear view being a mirror image; FIG. 3 is a right side view thereof, the left side view being a mirror image; FIG. 4 is a top view thereof; and, FIG. 5 is a bottom view thereof.

The broken lines are included for the purpose of illustrating portions of the tissue suspension adaptor and form no part of the claimed design.
